SWITCH CONSTRUCTION

Glenn R. Runke, Racine, Wis., assignor to Line Material Company, South Milwaukee, Wis., a corporation of Delaware

Application May 21, 1943, Serial No. 487,883

18 Claims. (Cl. 200—116)

1

This invention relates to a switch construction. In greater detail, this invention relates primarily to a switch construction of the circuit breaker type.

Objects of this invention are to provide a circuit breaker which has a quick make and a quick break, which has condition responsive means of the trip type, which is so constructed that it releases the circuit breaker so that the circuit breaker will open under predetermined conditions, and which is provided with a handle or other operating means for normally opening and closing the circuit breaker and for resetting the trip means, the trip means and the operating means being so related that the trip means will operate to release the circuit breaker irrespective of the position of the operating means and irrespective of any motion that the operating means may be executing at the time the trip means operates so that the trip means is trip free and will operate no matter whether the operating means is forcibly held in closed position or is being moved from one position to another.

Further objects are to provide a circuit breaker which is so constructed that the circuit breaker cannot be closed until the trip means has moved back to normal position, and in which the resetting of the trip means is accomplished by moving the operating means towards open position, such motion being followed by movement to closed position after the resetting of the trip means when it is desired to again close the circuit breaker after the occurrence of the predetermined condition.

Further objects are to provide a construction in which the trip means may be either thermostatically or magnetically or otherwise operated and which has either a quick action or a delayed action and which is adjustable so that the condition to which it will respond may be predetermined.

Further objects are to provide a circuit breaker which has a heavy contact pressure when it is closed, in which this heavy contact pressure is maintained during the operation of the circuit breaker until the instant at which the contacts are suddenly separated, thereby avoiding burning of the contacts under overload conditions.

Further objects are to provide a circuit breaker in which the mechanism is so arranged that it is easy to operate in opening and closing the circuit breaker and in resetting the trip means, and which is so made that there is no great wear on the parts during the opening and closing of the circuit breaker or during the resetting of the trip

2

means as the mechanism is so arranged that during resetting, for example, relatively small forces or pressures are exerted between the cooperating parts, thereby minimizing wear.

5 Further objects are to provide a circuit breaker in which the trip means is required to exert only a very small force in order to cause automatic operation, the relation of the parts insuring retatching without any chance of wedging or jamming either the trip mechanism as a whole or any portion of the latch means.

In circuit breakers of the toggle link type, as heretofore constructed, it has been a common practice to pivot one end of the toggle link mechanism at one point and deliver the force due to the toggle action from the other pivoted end of the toggle link mechanism. This old arrangement produced a true toggle action.

Further objects of this invention are to provide 20 a switch which may be of the circuit breaker type with mechanism which includes a pair of members pivoted together with the outer end of one of the members pivoted at one point and with the other member constituting a follower and mounted so that it is merely guided and arranged to carry the movable contact, and to so organize and arrange the mechanism that there is no toggle action until the movable contact engages a stationary contact and to have yielding 25 means for one of the contacts.

Further objects are to provide a circuit breaker which does not require the collapse of a toggle mechanism when it is automatically released, as on overload for instance, but in which a follower is suddenly directly pulled by spring means away 30 from the stationary contact to thereby secure a very quick break so that the speed with which the contacts are separated, even at the initial portion of the movement of separation, is greater than that which would have been provided by the collapse of a toggle mechanism arrangement.

Further objects are to provide a circuit breaker construction which is sturdy and is reliable in 35 operation, which may be installed in a transformer case and submerged in the oil in the transformer case if desired, and which if a thermostatic trip means is employed, may be arranged to have the thermostatic means respond 40 solely to the heat generated by current passing through the thermostatic means or to the combined action of the heat in the oil from the transformer or other device as well as from the heat due to the current passing through the thermostatic means, or may be arranged to respond 45 solely to the heat of the oil.

Embodiments of this invention are shown in the accompanying drawings, in which:

Figure 1 is a sectional view through the circuit breaker, such view corresponding approximately to a section on the line 1—1 of Figure 2 and showing the circuit breaker in closed position, one of the upper links being sectioned off.

Figure 2 is a plan view of the circuit breaker with a part of the main operating means sectioned off.

Figure 3 is a view corresponding to Figure 1 showing the circuit breaker after it has been manually opened.

Figure 4 is a view corresponding approximately to Figure 1 showing the circuit breaker after it has been automatically opened, such view, however, having parts broken away and having both of the upper links shown.

Figure 5 is a fragmentary detail showing the thermostatic means.

Figure 6 is a view showing the circuit breaker mounted in a transformer casing.

Figure 7 is a sectional view on the line 7—7 of Figure 6.

Figure 8 is a view showing another manner in which the circuit breaker may be mounted.

Figure 9 is a wiring diagram.

Figure 10 is a view of a further form of condition responsive means.

Before proceeding with the detailed description of this invention it is to be understood that the circuit breaker may have either a single switch means or a plurality of switch means, a circuit breaker with a single switch means having been chosen for the sake of illustration.

Referring to the drawings, it will be seen that the circuit breaker comprises an insulating body portion which has a base 1 and a pair of insulating upstanding walls 2 carried thereby. Between these walls a floating follower 3 is provided which is preferably formed of two spaced, generally triangularly shaped plates integrally joined by a transverse lower web 4 and also joined by a transverse upper web 5. Each side wall of the follower or member 3 is provided with an elongated slot 6 which is slidably guided by means of a pin 8 supported from the walls 2 and provided with a roller 7, so that the follower 3 may rock about the pin 8 or may have translatory motion with or without rocking, thereby constituting the follower a floating member.

A movable contact 9 is slidable through an aperture in the transverse web 4 and is spring urged downwardly by means of the spring 10 interposed between such movable contact 9 and the transverse web 5 and suitably centered as indicated in Figure 1. The movable contact is attached to a flexible leader or conductor 11. It is adapted to engage a stationary contact 12 which is provided with a terminal member 13. Obviously the contact 9 could be rigidly mounted on the follower and the contact 12 could be yieldingly supported.

A carrier 14 is mounted in spaced relation to the floating follower 3 and is pivotally mounted on a transverse pin 15, suitable spacer sleeves 16 being carried by the pin 15 to hold the carrier 14 centrally between the walls 2 of the body portion.

An upper link structure 17, which may be composed of a pair of separate links located on each side of the carrier 14, is pivoted on the pin 18 to the carrier 14 and is pivoted by means of a pin as indicated at 19 to the floating follower 3. Suitable spacer sleeves 20 are carried by the pin 19 and positioned between the links 17, and between

the links and the side walls of the follower 3. For the sake of clearness one of the links has been sectioned off in both Figures 1 and 3.

Main operating means in the form of a pair of levers 21 are pivoted on the pins 22 carried by the side walls 2 and are located on opposite sides of the channel-shaped floating follower 3. They are joined at their upper ends by means of a transverse pin 23. The main operating levers or means 21 are operated in any suitable manner. For example, they may be operated by means of insulating links 24 connected to rock arms 25. The rock arms 25 are rigidly mounted upon a rock shaft 26, see Figures 6 and 7, and the shaft 26 extends through the casing 27 of the transformer 28 and is provided with an operating handle 29 located externally of the transformer. This main operating means consisting of the levers 21 is adapted to be rocked from the full line position shown in Figure 1 to the dotted line position for opening the circuit breaker and is adapted to be rocked in the reverse direction for closing the circuit breaker, the closed position being shown in Figure 1 and the manually opened position being shown in Figure 3. A pin 30 is secured to the levers 21 and carries a reset roller or sleeve 31 whose purpose will hereinafter appear. Springs 32 extend between the pin 30 and the pin 19 and are always under tension. The ends of the springs 32 may be attached to members 30' and 19' through which the pins 30 and 19, respectively, pass. These springs are located on opposite sides of the carrier 14. It is to be noted that the carrier 14 is provided with a cam surface 33 which not only acts as a cam in a manner hereinafter to appear, but also acts as a stop, the sleeve or roller 31 engaging such surface as shown in dotted lines in Figure 1 and in full lines in Figure 3 to arrest the counterclockwise motion of the main operating means 21 when the circuit breaker is manually opened.

From the description thus far given it is apparent that when the main operating means 21 is rocked from the full line position shown in Figure 1 towards the dotted line position shown in Figure 1, which is the full line position shown in Figure 3, the line of pull of the springs will pass a line joining the center of the pins 18 and 19. When it has passed to the left beyond such line, it will pull the pivoted link 17 suddenly to the left, thus causing the circuit breaker to move to open position with a sudden motion, the manually opened position being shown in Figure 3.

During this operation it is necessary for the pivoted link 17 to slightly further compress the relatively heavy spring 10 and a considerable amount of energy is stored not only in the springs 32 but also in the spring 10, all of which springs are effective during the actual opening motion of the circuit breaker, the effect of the spring 10 assisting in initiating the opening and the effect of the springs 32 continuing throughout the entire opening stroke.

65 A slight sliding motion occurs between the floating follower 3 and the guiding pin 8.

When the main operating means 21 is rocked to the right from the full line position shown in Figure 3, it is apparent that when the line of pull of the springs 32 passes beyond the line joining the center of the pins 19 and 18, the mechanism composed of the pivoted link 17 and the floating follower 3 will suddenly rock to the right and close the switch with a quick action, slightly compressing the relatively heavy spring 10 and caus-

ing a slight sliding action to occur between the floating follower 3 and the guiding pin 8.

A peculiar action is to be noted at this point. Heretofore in toggle link mechanisms it is the usual practice to transmit the force from the pivoted end of one of the links of the toggle mechanism. In the construction forming the subject matter of this invention, it is to be noted that the follower 3 is a floating follower and merely floats with reference to the guiding pin 8. There is no toggle action whatsoever in the mechanism hereinabove described until the contacts are in actual engagement and then the toggle action is between the links 17, a portion of the floating follower 3 and the spring 10 and the movable contact 9 bearing against the stationary contact 12. During this portion of its operation the spring 10 is compressed and the movable contact 9 approaches nearer to the transverse member 5 than in the open position. Thus the effective arm, composed of a portion of the follower 3, the spring 10 and the movable contact 9, constitutes at most one link of a toggle link mechanism while the contacts are in actual engagement and such effective link shortens during the final portion of the closing motion of the circuit breaker.

It is to be noted that the follower 3 has both motion of translation and motion of rotation.

Motion to the right of the link 17 when the switch is in closed position is limited by engagement between the link 17 and the spacers 18 carried by the pin 15. From an examination of Figure 1 it is apparent that the axis of the pin 19 has moved slightly to the right of a line joining the center of the movable contact 9 and the pin 18 and consequently the mechanism tends to lock in this position as the line of pull of the springs 32 is to the right as viewed in Figure 1.

Means are provided for automatically opening the circuit breaker upon the occurrence of a predetermined condition, such for example as overload. This is accomplished by providing condition responsive means, such as the thermal element 34 which may be of inverted U-shape as shown in Figure 5 and which is provided with an upper insulating head portion 35 through which an adjusting screw 36 is threaded, such screw being provided with an insulating pin 37 adapted to release trip mechanism in a manner hereinafter to appear.

The flexible leader 11 is connected to one leg of the thermal element 34 and the terminal 38 is connected to the other leg of the thermal element. The thermal element is adapted to warp to the right as viewed in Figure 1 upon overload. The thermal element 34 may be of the common bimetallic type.

The latch mechanism may comprise a main latching lever 39, see Figure 1, which is pivoted on the pin 40 and is urged in a counterclockwise direction by means of the spring 41, a stop pin 42 being provided to limit the motion of the main latch lever 39 when released. The main latch lever is composed of two side members integrally joined by a transverse portion 43. It is provided with a latching pin 44 which engages the flat upper face of a latching lip 45 integral with the carrier 14, it being noted that such lip is provided with a rounded lower portion which is adapted to engage a transverse portion 46 of the main latching lever 39 in a manner and under conditions hereinafter to appear. Normally the main latch lever 39 is held in latched condition by means of an auxiliary latching lever 47 which is pivoted on the pin 48 and is spring urged

in a counterclockwise direction. It is provided with a pair of lower latching lips 49 which latch beneath the transverse portion 43 of the main latching lever and is provided with a transverse upper portion 50 against which the insulating portion or pin 37 of the adjusting screw 36 is adapted to bear.

It is to be noted that the latching pin 44 is arranged substantially vertically over the pivot pin 40 of the main latch lever and that the point of contact between the transverse portion 43 of the main latching lever and the latching lips 49 of the auxiliary lever is substantially vertically directly below the pivot pin 48 of the auxiliary latching lever. Thus frictional binding is minimized and a very small force is required to be exerted by the thermal element in order to trip the compound latching mechanism.

When an overload occurs, the thermal element 34 warps to the right to the position shown in Figure 4 and releases the main latch lever from the auxiliary latching lever, which in turn releases the carrier 14 from the main latch lever. The carrier suddenly rocks upwardly and the follower 3 is suddenly jerked upwardly by means of the springs 32, the initial portion of the upward motion being assisted by the spring 10. There is a slight rocking of the follower 3 due to the action of the link 17 but the release is primarily due to the direct upward motion of the follower 3. It will be seen that the floating follower 3 slides a considerable distance with reference to the guiding pin 8 during this upward motion upon comparing Figures 1 and 4.

It is to be noted that the main operating member 21 has rocked from the position shown in Figure 1 to the indicating position shown in Figure 4, thus indicating that the circuit breaker has automatically opened.

When it is desired to reset the circuit breaker, the main operating means 21 is rocked from the position shown in Figure 4 to the left and the sleeve or roller 31 rides upon the slanting cam face 33 of the carrier and forces the carrier downwardly. The carrier is forced downwardly slightly beyond the position shown in Figure 1 and the rounded lower face of the lip 45 of the carrier engages the transverse finger 46 of the main latching lever 39 and rocks such lever to a position where it will be latched by the auxiliary latching lever 47. Thereafter the main operating means 21 is allowed to move slightly to the right and the carrier rises and its lip 45 latches beneath the pin 44 as shown in Figure 1.

No binding or wedging of the latch mechanism and no undue stressing of the thermal element can occur as the portion 43 of the main latch lever never leaves contact with the auxiliary latch lever 47 and clockwise motion of the main lever 39 does not impose any strain on the auxiliary latch lever 47. Obviously if the thermal element has not cooled, it will not be distorted even if it is attempted to close the circuit breaker.

The circuit breaker may be mounted directly upon the transformer 28, as shown in Figure 6, and may be operated by means of the externally located handle 29, see Figure 7, as previously described. The circuit breaker may be mounted below the oil level indicated at 51 in Figure 6 so that the switch is operated in oil and so that the thermostatic element may be heated not only by the current passing therethrough but by the general temperature of the oil. The purpose of this is to allow the thermostatic element to respond not only to a relatively sudden overload but to

allow it to respond to the gradual rise of temperature of the oil which would result from a small and prolonged overload due to the heating of the transformer itself. Thus there may be afforded the double protection of opening of the switch under the influence of an overload of reasonable magnitude or the opening of the switch from a prolonged small overload due to the heating of the transformer. It is obvious also that if desired the main current need not pass through the thermal member and the thermal member could then respond merely to the heat of the oil if so desired or the oil level could be so regulated that it is below the thermal member and then the thermal member would respond merely to the heat from the current passing therethrough.

The circuit breaker is also adapted for wall mounting. For example it may be mounted within a casing 52, as shown in Figure 8, and an insulating handle 53 may extend through the curved wall of the casing and may be directly attached to the operating member 21, which corresponds to the operating member 21 hereinbefore described.

Figure 9 shows a wiring diagram in which the circuit breaker contacts 12 and 9 and the thermal element 34 are connected in series with the secondary 54 of the transformer 28.

Obviously other forms of condition responsive means may be employed. For instance a solenoid type of condition responsive means is shown in Figure 10 in which the solenoid 55 is adapted to raise the plunger 56 to thereby operate the bell crank lever 57 and move the adjusting screw 58 into contact with the auxiliary trip lever in the same manner as that hereinbefore described.

It is to be understood that the expression "condition responsive means" includes not only the thermostatic member shown but also the associated levers or latch mechanism.

Any suitable form of time delay means may be provided such as the piston 59 connected to the plunger 56 and mounted within the cylinder 60, suitable apertures being provided in the cylinder for the fluid and a suitable spring 61 being provided for returning the plunger to its lowermost position. The purpose of the time delay is to prevent the circuit breaker from suddenly opening for any sudden and extremely transitory overload for instance, but to allow the circuit breaker to open as promptly as desired for an overload for a period longer than that for which the time delay has been designed.

It is apparent that the value of the condition to which the circuit breaker may respond may be determined by the setting of the adjusting screws 36, Figure 1, or 58, Figure 10.

Other time delay means of course could be employed and it is to be distinctly understood that the circuit breaker could be made to respond to over or under voltage, overload, phase reversal, or any other desired condition.

The circuit breaker chosen for illustration is a single switch unit type but obviously, as hereinbefore stated, the circuit breaker may be either a single or multiple switch type without departing from the spirit of this invention.

Although this invention has been described in considerable detail, it is to be understood that such description is intended as illustrative rather than limiting, as the invention may be variously embodied and is to be interpreted as claimed.

I claim:

1. A switch construction comprising a floating,

8
pivotally mounted follower operatively connected to a movable contact, a co-operating contact adapted to be engaged and disengaged by said movable contact, a link having one end pivoted to said follower and having the other end pivoted at a point spaced from said follower, and main operating means for rocking said link, said link and said floating follower having a toggle action only when said contacts are in engagement.

5 2. A switch construction comprising a floating, pivotally mounted follower operatively connected to a movable contact, a cooperating contact adapted to be engaged and disengaged by said movable contact, a link having one end pivoted to said follower and having the other end pivoted at a point spaced from said follower, main operating means, and spring means operatively joining said link and said main operating means for rocking said link when said main operating means is moved, said link and said floating follower having a toggle action only when said contacts are in engagement.

10 3. A switch construction comprising a floating, pivotally mounted follower operatively connected to a movable contact, a cooperating contact adapted to be engaged and disengaged by said movable contact, a link having one end pivoted to said follower and having the other end pivoted at a point spaced from said follower, main operating means, and spring means operatively joining said link and said main operating means for rocking said link when said main operating means is moved, said link and said floating follower having a toggle action only when said contacts are in engagement.

15 4. A switch construction comprising a floating follower operatively connected to a movable contact, a cooperating contact adapted to be engaged and disengaged by said movable contact, a link having one end pivoted to said follower and having the other end pivoted at a point spaced from said follower, means for guiding said follower and allowing both rotational and translatory motion of said follower, and main operating means for rocking said link, said link and said floating follower having a toggle action only when said contacts are in engagement, the line of thrust when said toggle action occurs extending directly from the spaced point through said contacts.

20 5. A switch construction comprising a floating follower operative connected to a movable contact, a cooperating contact adapted to be engaged and disengaged by said movable contact, a link having one end pivoted to said follower and having the other end pivoted at a point spaced from said follower, said follower having a slot, guiding means extending through said slot, and main operating means for rocking said link, said link and said floating follower having a toggle action only when said contacts are in engagement, the line of thrust when said contacts are in engagement extending directly through said contacts.

25 6. A switch construction comprising a floating, pivotally mounted follower operatively connected to a movable contact, a cooperating contact adapted to be engaged and disengaged by said movable contact, a link having one end pivoted to said follower and having the other end pivoted at a point spaced from said follower, and main operating means for rocking said link, said link and said floating follower having a toggle action only when said contacts are in engagement, the line of thrust when said contacts are in engagement

extending directly through said contacts, one of said contacts being yielding.

7. A switch construction comprising a floating, pivotally mounted follower, a movable contact yieldingly carried by said floating follower, a co-operating contact adapted to be engaged and disengaged by said movable contact, a link having one end pivoted to said follower and having the other end pivoted at a point spaced from said follower, main operating means for rocking said link back and forth across a line joining the spaced point and the said cooperating contact, said link and said floating follower having a toggle action only when said contacts are in engagement.

8. A switch construction comprising a floating, pivotally mounted follower, a movable contact yieldingly carried by said floating follower, a co-operating contact adapted to be engaged and disengaged by said movable contact, a link having one end pivoted to said follower and having the other end pivoted at a point spaced from said follower, main operating means for rocking said link back and forth across a line joining the spaced point and the said cooperating contact, said link and said floating follower having a toggle action only when said contacts are in engagement, the line of thrust when said toggle action occurs extending directly from the spaced point through said contacts.

9. A switch construction comprising a stationary contact, a floating, pivotally mounted follower, a movable contact carried by said floating follower, spring means carried by said floating follower and urging said movable contact outwardly with reference to said floating follower, said movable contact being adapted to engage and disengage said stationary contact, a link having one end pivoted to said follower and having the other end pivoted at a point spaced from said follower, and main operating means for rocking said link back and forth across a line joining said stationary contact and the spaced point, said link and said floating follower having a toggle action only when said contacts are in engagement.

10. A circuit breaker comprising a stationary contact, a floating follower having a movable contact adapted to engage and disengage said stationary contact, a movable carrier, condition responsive means normally holding said carrier against motion and releasing said carrier upon the occurrence of a predetermined condition, said carrier being biased for motion away from said stationary contact, a link pivoted to said carrier and to said follower, and main operating means for rocking said link back and forth across a line joining the point at which said link is pivoted to said carrier and said stationary contact, said link and said floating follower having a toggle action only when said contacts are in engagement.

11. A circuit breaker comprising a stationary contact, a floating follower having a movable contact adapted to engage and disengage said stationary contact, a movable carrier, condition responsive means normally holding said carrier against motion and releasing said carrier upon the occurrence of a predetermined condition, said carrier being biased for motion away from said stationary contact, a link pivoted to said carrier and to said follower, and main operating means for rocking said link back and forth across a line joining the point at which said link is pivoted to said carrier and said stationary contact, said link and said floating follower having a toggle

action only when said contacts are in engagement, the line of thrust when said contacts are in engagement extending directly through said contacts.

5. 12. A circuit breaker comprising a stationary contact, a floating follower, a movable contact yieldingly carried by said floating follower and adapted to engage and disengage said stationary contact, a movable carrier mounted in spaced relation to said floating follower and biased towards motion in a direction outwardly from said floating follower, condition responsive means normally holding said carrier against motion and releasing said carrier upon the occurrence of a predetermined condition, a link having one end pivoted to said follower and having the other end pivoted to said carrier, and main operating means for rocking said link back and forth, said link and said floating follower having a toggle action only when said contacts are in engagement.

20 13. A circuit breaker comprising a stationary contact, a floating follower, a movable contact yieldingly carried by said floating follower and adapted to engage and disengage said stationary contact, a movable carrier mounted in spaced relation to said floating follower and biased towards motion in a direction outwardly from said floating follower, condition responsive means normally holding said carrier against motion and releasing said carrier upon the occurrence of a predetermined condition, a link having one end pivoted to said follower and having the other end pivoted to said carrier, and main operating means for rocking said link back and forth, said link and said floating follower having a toggle action only when said contacts are in engagement, the line of thrust when said toggle action occurs extending directly from the point at which said link is pivoted to said carrier through said contacts.

25 14. A circuit breaker comprising a stationary contact, a floating follower, a movable contact yieldingly carried by said floating follower and adapted to engage and disengage said stationary contact, a movable carrier mounted in spaced relation to said floating follower and biased towards motion in a direction outwardly from said floating follower, condition responsive means normally holding said carrier against motion and releasing said carrier upon the occurrence of a predetermined condition, a link having one end pivoted to said follower at a point fixed with relation to said follower and having the other end pivoted to said carrier, and main operating means for rocking said link back and forth, said link and said floating follower having a toggle action only when said contacts are in engagement.

30 15. A circuit breaker comprising a stationary contact, a floating follower, a movable contact yieldingly carried by said floating follower and adapted to engage and disengage said stationary contact, a movable carrier mounted in spaced relation to said floating follower and biased towards motion in a direction outwardly from said floating follower, condition responsive means normally holding said carrier against motion and releasing said carrier upon the occurrence of a predetermined condition, a link having one end pivoted to said follower at a point fixed with relation to said follower and having the other end pivoted to said carrier, and main operating means for rocking said link back and forth, said link and said floating follower having a toggle

action only when said contacts are in engagement, the line of thrust when said toggle action occurs extending directly from the point at which said link is pivoted to said carrier through said contacts.

16. A circuit breaker comprising a stationary contact, a floating follower, a movable contact carried by said floating follower, spring means carried by said floating follower and urging said movable contact outwardly with reference to said floating follower, said movable contact being adapted to engage and disengage said stationary contact, a movable carrier mounted in spaced relation to said floating follower and biased towards motion in a direction outwardly away from said floating follower, condition responsive means normally holding said carrier against motion and releasing said carrier for motion upon the occurrence of a predetermined condition, a link pivoted to said carrier and pivoted to said floating follower, and main operating means for rocking said link back and forth across a line joining said stationary contact and the point at which said link is pivoted to said carrier, said link and said floating follower having a toggle action only when said contacts are in engagement.

17. A circuit breaker comprising a stationary contact, a floating follower having a movable contact adapted to engage and disengage said stationary contact, a movable carrier, condition responsive means normally holding said carrier against motion and releasing said carrier upon the occurrence of a predetermined condition, a link pivoted to said carrier and to said follower, movable main operating means, and spring means joining said main operating means and said link

adjacent the point where said link is pivoted to said floating follower, said main operating means being adapted to rock said link back and forth through the agency of said spring means, said link and said floating follower having toggle action only when said contacts are in engagement, said spring means biasing said carrier towards motion in a direction outwardly from said floating follower and said main operating

means moving to an indicating position under the influence of said spring means upon the release of said carrier.

18. A switch construction comprising a floating follower operatively connected to a movable contact, a cooperating contact adapted to be engaged and disengaged by said movable contact, a link having one end pivoted to said follower and having the other end pivoted at a point spaced from said follower, and main operating means for rocking said link about said spaced point without causing motion of said spaced point, said link and said floating follower having a toggle action only when said contacts are in engagement.
